US00D492480S1

(12) **United States Design Patent** (10) Patent No.: **US D492,480 S**
(45) Date of Patent: **** Jul. 6, 2004**

(54) **HANDBAG**

(75) Inventor: **Raphaëlle Hanley**, Paris (FR)

(73) Assignee: **Louis Vuitton Malletier**, Paris (FR)

(**) Term: **14 Years**

(21) Appl. No.: **29/191,491**

(22) Filed: **Oct. 7, 2003**

(51) LOC (7) Cl. **03-01**

(52) U.S. Cl. **D3/243**

(58) Field of Search D3/232, 233, 239,
D3/240, 241, 243, 245, 246, 303; D9/305;
150/100, 107, 108, 110, 111, 114; 190/16,
19, 100, 103, 104, 106, 112, 115, 116,
119, 121, 900, 901, 902, 903; 383/42, 84,
86, 98, 99, 104, 105, 119, 120, 121.1, 127

FIG. 4

UNITED STATES PATENT AND TRADEMARK OFFICE
CERTIFICATE OF CORRECTION

PATENT NO. : Des. 492,480 S
APPLICATION NO. : 29/191491
DATED : July 6, 2004
INVENTOR(S) : Hanley

Page 1 of 6

It is certified that error appears in the above-identified patent and that said Letters Patent is hereby corrected as shown below:

The title page showing an illustrative figure, should be **deleted** and substitute therefore the attached title page.

Delete drawing sheets 1 through 4 and substitute therefore the drawing sheet consisting of figs. 1 – 4 as shown on the attached page.

Signed and Sealed this

Thirtieth Day of September, 2008

JON W. DUDAS
Director of the United States Patent and Trademark Office
